Primary Examiner — Karen E Kearney*Assistant Examiner* — Dina Michelle Hoeynck(74) *Attorney, Agent, or Firm* — Wood Herron & Evans LLP(57) **CLAIM**

The ornamental design for an infrared sensor lens as shown and described.

DESCRIPTION

FIG. 1 is an isometric view of my new infrared sensor lens showing my new design with environmental structure; FIG. 2 is an isometric view thereof; FIG. 3 is a top plan view thereof; and, FIG. 4 is a front elevation view thereof, with the rear, right side, and left side views being identical. The broken dash lines shown in FIG. 1 are for illustrative purposes only and represent non-claimed environmental structure. Neither the portions of the environmental structure shown in broken dash line nor the broken dash lines themselves form any part of the claimed design.
